SOAP CHIP DISPENSER

Richard M. Storer, Denver, Colo.

Application March 5, 1942, Serial No. 433,483

11 Claims. (Cl. 146—62)

This invention relates to a device for producing chips or flakes from bar soap, and more particularly relates to a device of this character that is specially suited for household use.

While chips or flakes are now available on the market in convenient packages for household use, the cost of a given quantity of such packaged soap is substantially greater than the cost of an equivalent weight of bar soap in a corresponding grade.

It is an object of the present invention to provide a device that can be utilized to produce chips or flakes of soap from bar soap in a size suited for rapid dissolution or dispersion throughout a liquid body in which they are deposited.

Another object of the invention is to provide a device which is capable of producing a substantially uniform sized soap flake product over long periods of operation despite substantial variations in the size, composition and moisture content of the soap bars from which such flakes are produced.

A further object of the invention is the provision of a simple, durable and relatively inexpensive device that is positively and easily operated by persons not having special mechanical knowledge.

Still another object of the invention is the provision in a device of this character of a cutter member having a self-cleaning action.

A still further object of the invention is the provision of a device for producing soap flakes from bars that is uniformly efficient in the treatment of soap bars varying widely in size and quantity.

Other objects reside in novel details of construction and novel combinations and arrangements of parts, all of which will appear more fully in the course of the following description.

To afford a better understanding of the invention, reference is made to the accompanying drawing illustrating a typical embodiment of the invention, and in the drawing in the several views of which like parts have been designated similarly,

Figure 1 is a bottom plan view, partially in section, of a device embodying the features of the present invention;

Figure 2 is a side elevation of the device of Figure 1, partially broken away to show the interior mechanism;

Figure 3 is a section taken along the line 3—3, Figure 2;

Figure 4 is a section taken along the line 4—4, Figure 2, and drawn to an enlarged scale;

Figure 5 is a fragmentary section taken along the line 5—5 of Figure 4;

Figure 6 is a fragmentary section taken along the line 6—6 of Figure 5; and

Figure 7 is an end view of one of the cutter blades illustrated in Figures 4 and 5.

The device illustrated in the drawing comprises a casing 8 open at one end as indicated at 9, for the reception of a bar of soap and having its opposite end closed by a cutter member 10. After a bar of soap has been inserted in the casing through open end 9, a closure member 12 is inserted in the casing to urge the bar of soap 13 against cutter member 10.

This closure member 12 comprises a plate 12a carrying socket members 14 in which sprung-urged pins 15 are supported for extension through a series of openings 16 in casing 8. Movement of the pins 15 to a retracted position may be effected through manual actuation of grips 17 connected therewith. A spring 18, preferably a coil spring, is mounted on plate 12a and bears against another plate 19 substantially corresponding to the interior size of casing 8 but slightly spaced therefrom.

Casing 8 is apertured, as indicated at 20 in Figure 3, and a narrow slot 21 extends into this apertured portion at right angles to its lengthwise axis. A pin 22 mounted on an angle plate 23 carries externally of casing 8 a knurled knob 24 permitting adjustment of plate 23 to different selective positions within casing 8 in engaging relation to the bar of soap 13.

Such adjustment is further facilitated by provision of a recess 25 in plate 19 permitting its extension in close proximity to cutter 10, even when angle plate 23 is moved to its extreme position away from the wall of casing 8. To prevent tilting of angle plate 23, a portion of said plate is bent to form lugs 32 fitted in slot 21 for sliding movement, but holding the same against movement away from the wall of casing 8.

Cutter member 10 comprises a frame 26 mounted for sliding oscillatory movement along flanged ends 27 of casing 8, and such oscillatory movement is controlled through actuation of a crank assembly 28. The frame at its sides has a series of substantially triangular-shaped recesses 29 (Figure 6) and a series of cutter blades 30 are disposed in such recesses throughout the length of frame 26. As best seen in Figure 4, the cutter blades 30 are of a corrugated or undulating contour having recessed cutting edges 30a and adjoining projecting portions 30b, the reverse side

of which is recessed as indicated at 30c in Figure 4.

In assembling the cutter blades, a staggered arrangement is employed, as best illustrated in Figure 5, in which the surfaces 30a of one cutter blade will be aligned with the projections 30b of the next succeeding blade in the series to bring recesses 30c in register therewith. As illustrated in Figures 5 and 7, the ends of the cutter members 30 terminate in flattened portions 31 and these portions 31 are loosely fitted in recesses 29, due to the shape of the latter, to permit angular movement therein. As illustrated in Figure 1, this assembly of cutter members is arranged to form a honeycomb pattern of discharge passages for the cut soap.

With this arrangement, movement imparted to frame 26 by crank assembly 28 in a direction transverse to the bar of soap 13 being pressed against blades 30 by spring-urged plate member 19, will cause a turning of blade members 30 which brings the cutting surfaces 30a into downwardly inclined engagement with the surface of soap 13 in the direction of movement of frame 26.

When the frame has reached its furthermost position under actuation by the crank and commences its return movement in the oscillatory cycle, the blades 30 again reverse their positions by rotation of portions 31 within recesses 29 and the forward cutting surfaces 30a are again downwardly inclined into the bar of soap 13.

The device hereinbefore described is intended primarily for household usage and can be operated readily when the user holds the casing in one hand and operates the crank assembly 28 with the other hand. When so operated, the device may be conveniently transported from one location to another wherever its use is required.

However, it will be understood that when desired the casing may be more or less permanently located by attachment to a wall bracket or other suitable device in any selected position of use.

Because of the adjustments provided, soap of various sized bars may be effectively treated in the device. When a bar is selected for use, it is inserted through open end 9 of the casing after which plate member 12 is inserted through opening 9 and moved to a position in which plate 19 is exerting considerable pressure against the bar of soap. The operator thereupon releases pressure against grips 17 allowing pins 15 to project through whatever aligned openings 16 are adjacent thereto, and until sufficient soap has been removed from the end of bar 13 by the cutting action, further adjustment of closure member 12 will not be required.

If the bar of soap 13 thus inserted is of a size permitting lateral movement within casing 8, angle plate 23 is moved through loosening of knurled knob 24 to a position in which it bears firmly against the cake of soap 13 and holds its opposite surface in contact with the wall of casing 8. When so positioned, knob 24 is tightened.

After this loading operation has been completed, the device is adapted for a considerable period of use without further adjustment and it will be apparent that whenever plate member 19 ceases to exert adequate pressure against the bar of soap 13, an adjustment of the position of such plate can be effected in the manner described, to again exert the desired degree of pressure.

While such pressure is being exerted, actuation of the crank assembly 28 will cause the oscillating movement of frame 26 previously described, with the cutting surfaces of blade members 30 moving across the surface of soap 13 in a direction transverse to its lengthwise axis, with the cutting surfaces disposed at an inclination to such surface of the soap.

The resulting action causes the cut soap to 10 pass through the spaces between cutter members 30 in flakes of relatively fine thickness. These flakes are relatively long in comparison with their width and thickness and tend to curl, causing them to break freely from the portions being cut after they have assumed a length of from one-fourth inch to one inch.

The repeated turning of the blades resulting from changes in direction of frame 26 in its oscillating action, further facilitates discharge of 20 the cut portions and exerts a self-cleaning action on the cutter assembly which is particularly advantageous when the device is operating on soap of relatively high moisture content which otherwise might tend to wedge in the spaces between the blades and impair continued operation.

Likewise, the provision of recesses 30c at the trailing edge of cutter members 30 serves to ridge the soap between the cuts being made at 30 the forward edge, and due to the staggered arrangement of cutting surfaces on successive cutter members, the ridge so produced is removed by the next succeeding cutting surface.

While the undulating cutting surfaces illustrated in the drawing are a preferred embodiment, the turning and tilting of cutter blades 30 alone is sufficient to produce an adequate cutting and cleaning action.

Changes and modifications may be availed of 40 within the spirit and scope of the invention as defined in the hereunto appended claims.

What I claim and desire to secure by Letters Patent is:

1. A device of the character described, comprising a container for a cake of soap, an oscillatory cutter member providing a closure for a side of the container, means associated with the container for pressing a cake of soap therein against said cutter member said soap pressing means and said cutter member cooperating to discharge cut soap from the container, said cutter member comprising a plurality of spaced-apart cutters having discharge openings for the lateral discharge of cut soap therebetween, each such cutter having forward cutting surfaces penetrating the cake of soap in each direction of travel of the cutter member, and means for changing the angular position of said cutters during each change in direction in the oscillatory cycle of the cutter member to effect the soap penetration by said forward cutting surfaces.

2. A device of the character described, comprising a container for a cake of soap, an oscillatory cutter member providing a closure for a side of the container, means associated with the container for pressing a cake of soap therein against said cutter member said soap pressing means and said cutter member cooperating to discharge cut soap from the container, means in the container 65 for holding the soap bar against movement transversely of the container, said cutter member comprising a plurality of spaced-apart cutters having discharge openings for the lateral discharge of cut soap therebetween, each such cutter having forward cutting surfaces penetrating the cake of

soap in each direction of travel of the cutter member, and means for changing the angular position of said cutters during each change in direction in the oscillatory cycle of the cutter member to effect the soap penetration by said forward cutting surfaces.

3. A device of the character described, comprising a container for a cake of soap, an oscillatory cutter member providing a closure for a side of the container, means associated with the container for pressing a cake of soap therein against said cutter member said soap pressing means and said cutter member cooperating to discharge cut soap from the container, adjustable means within the container mounted for movement to selective positions of engagement with said soap bar to hold the same against movement transversely of the container, said cutter member comprising a plurality of spaced-apart cutters having discharge openings for the lateral discharge of cut soap therebetween, each such cutter having forward cutting surfaces penetrating the cake of soap in each direction of travel of the cutter member, and means for changing the angular position of said cutters during each change in direction in the oscillatory cycle of the cutter member to effect the soap penetration by said cutting surfaces.

4. A device of the character described, comprising a container for a cake of soap, an oscillatory cutter member providing a closure for a side of the container, means associated with the container for pressing a cake of soap therein against said cutter member said soap pressing means and said cutter member cooperating to discharge cut soap from the container, said cutter member comprising a plurality of spaced-apart tiltable cutters having discharge openings for the lateral discharge of cut soap therebetween, each such cutter having undulating cutting surfaces penetrating the cake of soap in each direction of travel of the cutter member, and means for tilting said cutters during each change in direction in the oscillatory cycle of the cutter member to incline the forward undulating surfaces downwardly as they penetrate the soap.

5. A device of the character described, comprising a container for a cake of soap, an oscillatory cutter member providing a closure for a side of the container, means associated with the container for pressing a cake of soap therein against said cutter member said soap pressing means and said cutter member cooperating to discharge cut soap from the container, said cutter member comprising a plurality of spaced-apart tiltable cutters having discharge openings for the lateral discharge of cut soap therebetween, each such cutter having double-edged cutting surfaces with the leading edge thereof penetrating the cake of soap, and means for tilting said leading edges into soap penetrating relation during each change in direction in the oscillatory cycle of the cutter member.

6. A device of the character described, comprising an elongated container for a cake of soap, a cutter member mounted for limited oscillatory movement at the end of the container transversely of its lengthwise axis and providing a closure for said end of the container, means associated with the container for urging a cake of soap therein toward said cutter member, said soap pressing means and said cutter member cooperating to discharge cut soap from the container, said cutter member comprising a plurality of spaced-apart cutters having discharge openings

for the lateral discharge of cut soap therebetween, each having forward cutting surfaces penetrating the cake of soap in each direction of travel of the cutter member, mechanism connected with the cutter member to impart oscillatory movement thereto, and means responsive to each change in direction in the oscillatory cycle of the cutter member for rocking the cutters to a position in which said forward cutting surfaces penetrate the soap.

5 7. A device of the character described, comprising a container for a cake of soap, an oscillatory cutter member providing a closure for a side of the container, means for pressing a cake of soap in the container into said cutter member, said soap pressing means and said cutter member cooperating to discharge cut soap from the container, said cutter member including tiers of cutters constructed and arranged to provide 15 a honeycomb pattern of cutting surfaces penetrating the cake of soap and having discharge openings for the lateral discharge of cut soap between the tiers, and means cooperative with said cutters for changing the angular position 25 of each tier in each direction of the oscillatory movement to effect soap penetration during opposed movements in the oscillatory cycle.

8. In a device of the character described, including a container for a cake of soap, an oscillatory cutter member mounted on the container in contacting relation to the soap and comprising an open frame formed of side members and end members, said side members having a series of substantially triangular-shape recesses therein arranged in cooperative, alined pairs, and a plurality of spaced cutter members supported by the frame member, each cutter member having flattened portions at its opposite ends fitted for turning movement in an alined pair of said recesses, and double-edged cutting surfaces intermediate said flattened ends.

30 9. A device of the character described, comprising a rectangular container for a cake of soap, an oscillatory cutter member providing a closure at an end of the container, means including a coil spring associated with the container for pressing a cake of soap therein against said cutter member, said cutter member comprising a plurality of spaced-apart cutters having 35 discharge openings for the lateral discharge of cut soap therebetween, each such cutter having forward cutting surfaces penetrating the cake of soap in each direction of travel of the cutter member, and means for changing the angular position of said cutters during each change in direction in the oscillatory cycle of the cutter member to effect soap penetration by different cutting surface with each said change in the cycle.

45 10. In a device of the character described, including a container for a cake of soap, an oscillatory cutter member mounted on the container in contacting relation to the soap and comprising an open rectangular frame formed of side members and end members, said side members having a series of substantially triangular-shaped recesses therein arranged in cooperative alined pairs, and a plurality of spaced cutter members supported by the frame member as a rectangular closure for said open end of the frame, each cutter member having flattened portions at its opposite ends fitted for turning movement in an alined pair of said recesses, and double-edged cutting surfaces intermediate said flattened ends.

11. In a device of the character described, a soap cutting element comprising a succession of elongated soap cutters arranged in tiers in closely spaced relation, for oscillatory cutting movement across an exposed surface of a cake of soap in said device, each cutter having a plurality of spaced cutting surfaces at intervals throughout

its length and raised portions disposed in the spaces between adjoining cutting surfaces of each cutter, said cutters being mounted for limited rotation to bring different cutting surfaces in engagement with the soap in each change in direction of said oscillatory movement.

RICHARD M. STORER.
